UNITED STATES PATENT OFFICE.

ALFRED K. HORTON, OF WICHITA, KANSAS.

DUSTER.

1,100,658.

Specification of Letters Patent. Patented June 16, 1914.

Application filed June 16, 1913. Serial No. 773,925.

To all whom it may concern:

Be it known that I, ALFRED K. HORTON, a citizen of the United States, residing at Wichita, in the county of Sedgwick and State of Kansas, have invented certain new and useful Improvements in Dusters; and I do hereby declare the following to be a full, clear, and exact description of the invention, such as will enable others skilled in the art 10 to which it appertains to make and use the same.

My invention relates to dusters for household use, and more particularly to novel and improved means for holding dust-cloths, 15 consisting of an extensible handle having an integral head designed and adapted to receive and securely retain a dust-cloth in operative relation.

It has for its object the production of an 20 appliance of the character stated, which is at once light and serviceable in construction, durable and economical to manufacture, and easily adjusted in length to meet varying conditions of use.

25 The invention will be hereinafter particularly described and pointed out in the claims following.

In the accompanying drawings which 30 form part of this application and whereon corresponding numbers indicate like parts in the several views, Figure 1 is a side elevation of my invention with dustcloth attached ready for service. Fig. 2 is a perspective view of the attaching head of my 35 invention with fabric removed, showing also a fragment of the extensible body members, the outermost of which being shown in section. Fig. 3 is a side elevation of the telescoping body member, and a dustcloth in 40 course of attachment, and, Fig. 4 is a relatively enlarged sectional view of the attaching end of duster and duster cloth assembled.

Reference being had to the drawings and 45 numerals thereon, 1 indicates a duster handle of wood or any suitable material, having a convenient hand gripping contour, and 2 a tubular extension or body member preferably of brass or other rust-proof material. 50 In telescopic relation with the member 2 is a second extensible body member 3 of like material, terminating at its outer end in an integral convolute 4 serving as a cloth attaching head, its opposite or inner end being 55 bent slightly as at 5, to insure frictional contact with, and a spring bearing upon, the

interior of tube 2 thereby preventing accidental separation of these telescoping members.

The numeral 6 indicates a dust-cloth of 60 any suitable fibrous or textile material, which, in the course of assembling, is first fed through convolute 4 substantially as shown by Fig. 3, whereupon the ends are folded over as shown by Fig. 4, and bound 65 in place by twine or ribbon 7 as shown by Figs. 1 and 4, in a manner to completely envelop convolute 4 and shield it from contact with articles dusted.

This being a description of my invention 70 it should be understood that cloth 6 may be variously applied and secured to head 4, and I do not therefore, limit my structure to the precise means shown, but contemplate the use of various equivalent means for accomplishing substantially the same results, 75 and to such in combination, lay claim the same as if specified.

The use of my invention is quite obvious, 80 it may, however, be noted that in dusting articles situated beyond the reach of ordinary duster handles, such, for example, as wall pictures, or the upper portion of chandeliers, my improved handle may be instantly extended to meet such conditions in 85 the following convenient manner: Handle 1 is grasped by one hand of the user, convolute 4 enveloped in cloth 6, being similarly grasped by the other hand, a pull in opposite directions now serves to withdraw the extensible body member 3, from within the tubular body member 2 until the required 90 extension is obtained. During either the withdrawal or replacement of body member 3 it will be seen that its bent inner end 5 is at all times in frictional engagement with 95 the interior of tube 2 thereby preventing any accidental displacement, or accidental relative movement of the telescoping parts aforesaid. The bend at 5 in extensible 100 member 3 referred to, is clearly shown by Fig. 2 of the drawings, and as will be seen such bend may be increased or decreased as a means of regulating the freedom with which the telescoping member 3 may be moved 105 within the tubular member 2.

Having thus described my invention, what I now claim and desire to secure by Letters Patent is:

1. As an article of manufacture a duster 110 for household use having a right angular bend at one end and an integral convolute

- head concentrically arranged with relation to the longitudinal axis of the duster, in combination with a dust cloth adapted to completely envelop said head.
- 5 2. As an article of manufacture a duster for household use, comprising telescoping body members, a bend in one of said members frictionally engaging the other of said members, and a dust-cloth secured to the 10 end of one of said body members.
3. As an article of manufacture a duster for household use, comprising a tubular body member, an extension member slidably longitudinally within said tubular member, 15 a bend in said extension member, and a dust-cloth secured to the end of said extension member.
4. As an article of manufacture a duster for household use, comprising a handle, a tubular body member projecting from said handle, an extension member slidably longitudinally within said tubular member, a bend near the inner end of said extension member in frictional engagement with the interior of the tubular body member, an enlarged head upon the outer end of the extension member, and a dust-cloth enfolded and secured to said head. 20 25

In testimony whereof I affix my signature, in presence of two subscribing witnesses.

ALFRED K. HORTON.

Witnesses:

M. F. CULLEN,
ROBERT H. STOTT.
